CLAIM

The ornamental design for a portable smoke detector or
similar article, as shown and described.

DESCRIPTION

FIG. 1 is a perspective view of a portable smoke detector or
similar article showing our new design;

FIG. 2 is a front elevational view thereof;

FIG. 3 is a left-side elevational view thereof;

FIG. 4 is a rear elevational view thereof;

FIG. 5 is a top plan view thereof;

FIG. 6 is a right-side elevational view thereof; and

FIG. 7 is a bottom plan view thereof.
